FIG. 1 is an isometric view of a catheter information clip
according to the present invention; a catheter is shown in
broken line for illustrative purposes only and forms no part of
the claimed design.

FIG. 2 is an isometric view of the catheter information clip
shown in FIG. 1, alone.

FIG. 3 is a proximal view of the catheter information clip
shown in FIG. 1;

FIG. 4 is a bottom view of the catheter information clip shown
in FIG. 1.

FIG. 5 is a top view of the catheter information clip shown in
FIG. 1;

FIG. 6 is a right side view of the catheter information clip
shown in FIG. 1; and,

FIG. 7 is a left side view of the catheter information clip
shown in FIG. 1.

A catheter is shown in phantom in FIG. 1 and is not part of the
invention claimed. The distal and proximal views are mirror
images of each other, and only the proximal view is shown.
